(57) **CLAIM**

The ornamental design for an anchor for a dive platform, as shown and described.

DESCRIPTION

FIG. 1 is a top of an anchor for a dive platform, according to the present invention;

FIG. 2 is a front elevational view of the anchor for a dive platform of FIG. 1;

FIG. 3 is a bottom view of the anchor for a dive platform of FIG. 1;

FIG. 4 is a left side elevational view of the anchor for a dive platform of FIG. 1;

FIG. 5 is a right side elevational view of the anchor for a dive platform of FIG. 1; and,

FIG. 6 is a perspective view of the anchor for a dive platform of FIG. 1.

The broken lines in FIGS. 2-5 are merely provided to indicate the hidden aspects of the design from the particular view and form no part of the claimed design.
